FIG. 1

FIG. 2

Howard J. Pruchnow Inventor

By Peter J. Gaynor Attorney

UNITED STATES PATENT OFFICE

153,822

DESIGN FOR A COMBINED VINE HOLDER AND WALL BRACKET THEREFOR

Howard J. Pruchnow, Summit, N. J.

Application October 30, 1947, Serial No. 142,232

Term of patent 14 years

(Cl. D35—3)

To all whom it may concern:

Be it known that I, Howard J. Pruchnow, a citizen of the United States, residing at Summit, in the county of Union and State of New Jersey, have invented a new, original, and ornamental Design for a Combined Vine Holder and Wall Bracket Therefor, of which the following is a specification, reference being had to the accompanying drawing, forming part thereof.

Fig. 1 is a front perspective view of a combined vine holder and wall bracket therefor showing my new design. Fig. 2 is a side perspective view of the same article.

I claim:

The ornamental design for a combined vine holder and wall bracket therefor, as shown.

HOWARD J. PRUCHNOW.
